UNITED STATES PATENT OFFICE.

GUSTAVE ADANT, OF BRUSSELS, BELGIUM.

MANUFACTURE OF SUGAR.

SPECIFICATION forming part of Letters Patent No. 444,107, dated January 6, 1891.

Application filed June 14, 1890. Serial No. 355,610. (No model.) Patented in Belgium October 7, 1887, No. 79,121; in France November 4, 1887, No. 186,785; in Germany December 31, 1887, No. 44,660, and in England September 10, 1888, No. 13,084, and May 4, 1889, No. 7,517.

To all whom it may concern:

Be it known that I, GUSTAVE ADANT, a citizen of Belgium, residing at Brussels, in Belgium, have invented certain new and useful Improvements in the Manufacture of Sugar, (for which I have obtained Letters Patent in Belgium October 7, 1887, No. 79,121; in France November 4, 1887, No. 186,785; in Germany December 31, 1887, No. 44,660, and in England September 10, 1888, No. 13,084, and May 4, 1889, No. 7,517;) and I do hereby declare the following to be a full, clear, and exact description of the invention, such as will enable others skilled in the art to which it appertains to make and use the same, reference being had to the accompanying drawings, and to letters of reference marked thereon, which form a part of this specification.

Referring to the drawings, Figure I is a vertical sectional elevation showing the basket or form in the filling-drum. Fig. II is a side and end view of one of the forcing-bars. Fig. III is a top plan view of Fig. I, the funnels being shown in dotted lines. Fig. IV is a vertical sectional elevation of the basket or form proper, illustrating the means of transporting the same when filled to the centrifugal. Fig. V is a vertical section of the centrifugal proper, and Fig. VI is a top plan view thereof. Fig. VII is a vertical section of the centrifugal with the basket or form secured thereto, and Fig. VIII is a top plan view thereof. Fig. IX is a vertical sectional elevation, and Fig. X a part plan and part cross-section of Fig. IX, the cover being removed and illustrating a modified construction of the form or basket and also means for clearing the blocks or cakes of sugar by steam. Fig. XI is a view illustrating the combination of devices or apparatus that constitute my improved system of purification.

This invention relates to the manufacture of sugar, and more particularly to the manufacture of tablets or slabs from which the cube or cut sugar is afterward obtained; and it has for its object to simplify this branch of sugar manufacture and effect a saving in material as well as in labor.

To these ends the invention consists in mak-

ing the form or basket detachable from the centrifugal and in constructing said form or basket so that it may be readily dismantled for the purpose of removing the purified slabs or tablets of sugar for the final drying preparatory to the cutting up thereof into cubes. In the construction of the centrifugal drum, so that the form or basket may be readily connected therewith or disconnected therefrom, and in minor details of construction, as will hereinafter be fully described, and in such description, for the sake of uniformity, I will refer to the form as the "basket" and to the combined basket and revoluble drum as the "centrifugal," as the drum without the basket would not constitute the centrifugal.

In the manufacture of the class of sugar referred to the processes and apparatus now generally in use are those of Langen, Mathey and Scheibler, Vivier, Tietz, and Selwig and Langen.

In the process of Langen perfectly white slabs or tablets are obtained by carrying the basket from the centrifugal to a clearing or purifying table after having been subjected to the action of the centrifugal in order to eliminate the green sirup, and this requires time and a considerable amount of labor on the one hand, and on the other considerable losses in view of the fact that the slabs are of trapezoidal form.

In the process of Mathey and Scheibler, after the impure or green sirup has been removed a partial vacuum is formed in the annular space of the centrifugal that contains the forms, and when the vacuum has reached about seventy-five centimeters mercury the clearing or fine liquor or sirup is admitted; but inasmuch as the liquor has access to the forms from within and from without some of the green sirup is forced inwardly by the fine liquor or sirup coming from without, so that the quantity of fine liquor supplied from within is insufficient to purify the sugar in the forms, and it becomes again necessary to subject from forty to sixty per centum of the slabs to centrifugal action, the sugar being usually yellow.

The process of Vivier does not differ very

materially from the above, while according to the mode of procedure of Tietz and Selwig and Langen the sugar is treated in the centrifugal four times, involving an inordinate expenditure of time and labor.

My improvements are designed to obviate the disadvantages referred to, and to this end the system of purification comprises a filling-drum D, in which the basket B is filled, a revolvable drum CD, to which the filled basket B is adapted to be connected, the two constituting the centrifugal, means for transporting the basket from the filling-drum to the revolvable drum, a reservoir R for the fine liquor arranged above the revolvable drum and at such an elevation as to supply the liquor under pressure to the basket, means for transporting the basket from the drum to a table or bench T, where it may be dismantled for the purpose of removing the purified cakes or tablets of sugar to be afterward dried, and means for connecting the reservoir containing the fine liquor with the revolvable drum and supplying the same under pressure to the basket, as shown in Fig. XI.

I will first describe the filling-drum D, reference being had to Fig. I. This drum is composed of two concentric drums d and d', forming between them an annular space for the reception of the basket B. The bottom of the drum between the inner and the outer walls has an annular recess d², the inner wall of which is inclined for the reception of a correspondingly-shaped base-rib on the bottom of the basket. The annular recess d² communicates with a passage d³, to which in practice is connected a valved exhaust-pipe, which I have deemed unnecessary to show, for exhausting the excess of masse-cuite from the drum in filling the basket. In the inner wall of the drum are formed vertical recesses d⁴, of which I have shown four, adapted to receive in their upper end a funnel F for the introduction of the fine liquor.

I will now describe the construction of the basket B, reference being had to Figs. I, III, IV, VII, and VIII.

The basket consists of a cylinder B² of the usual foraminous material, of a top plate or ring b', to which the upper end of the cylinder B² is secured, and of a bottom plate or ring b² upon a rabbet or shoulder of which the lower edge of said cylinder rests. The cylinder is divided vertically by eight wedge-shaped partitions b³ and b⁴, that project radially from the periphery toward the center of the basket to the extent of the width of the plates or slabs of sugar to be obtained, and the inclination of the sides of these partitions is such as to form a rectangular space between them, whose outer face is a segment of the circle described by the periphery of the basket, as more plainly shown in Figs. III and VIII, in which the partitions referred to are shown in dotted lines. The space between the partitions is again subdivided horizontally by

means of sheet-metal shelves B', that fit sufficiently tight between the wedge-shaped partitions as to hold them in position without further fastening, and the distance between said shelves will depend upon the thickness of the slabs of sugar to be obtained or the diameter of the cubes of sugar to be cut from said slabs. The partitions b³ are secured to the bottom ring b² in any suitable manner, and are connected with the top ring b' by means of hook or eye bolts b⁶, that pass through the ring and screw into the partitions. The partitions b⁴, on the contrary, simply seat on the bottom ring and have pins b⁵, that project from their upper face into holes in the top ring, and said partitions b⁴ are also secured to the top ring by means of hook or eye bolts b⁶ that likewise pass through the top ring and screw into the upper face of the said partitions b⁴. It is obvious that in the arrangement described if the hook or eye bolts b⁶ are unscrewed from the partitions b³ and the top ring lifted the partitions b⁴ will be lifted out of the basket, and as said partitions b³ b⁴ are arranged in alternate order the cakes or tablets of sugar can be readily removed, as hereinafter referred to.

As shown, the lower edge of the foraminous cylinder B² of the basket B is seated in an annular flange formed in the periphery of the bottom ring b² of said basket, and at its upper edge the said foraminous cylinder is rigidly secured to an overhanging flange formed on the top ring b'. Inasmuch as the partitions b³ are rigidly secured to the bottom ring b² of the basket it will be readily seen that by means of the hook or eye bolts b⁶ the parts that constitute the basket proper may be firmly yet detachably connected. On the other hand, by unscrewing the screw-bolts or eyes b⁶ that connect the partitions b³ to the top ring b' and by connecting said top ring through the medium of the hook or eye bolts b⁶ with a hoisting device, the top ring, the foraminous cylinder, and the partitions b⁴ may be lifted off, thus leaving the forms or shelves with the slabs of sugar thereon exposed for ready removal to the drier, which in practice will be convenient to the table T, upon which the basket is placed for such removal.

As will be readily comprehended, the partitions b³ and b⁴ not only determine the width and length of the slabs of sugar, but also serve as stiffening-braces for the foraminous cylinder B², so that as constructed the basket is adapted to be spun without danger of separation or disconnection of its parts.

On the under side of the bottom ring b² of the basket is formed an annular rib or foot b⁷, the inner face of which inclines inwardly, and, as hereinbefore stated, fits into a correspondingly-shaped recess in the bottom of the filling-drum D, and also upon a corresponding seat formed at the base of the centrifugal drum CD, to firmly seat the basket on said drum.

Above the table T is a rail R', that extends over the centrifugal drum CD, and the filling-drum D, Fig. XI, and Y, Figs. IV and XI, is a yoke suspended from a rack-bar RB, that 5 has motion in a holder H, provided at its upper end with carrier-wheels w, adapted to travel along the rail R', from which the holder is thus suspended. The rack-bar receives vertical motion in a well-known manner 10 through the medium of suitable gearing operated by a ratchet-lever L.

For the purpose of filling an empty basket the parts of the basket are united by lowering the top ring b', with the partitions b⁴ and 15 the foraminous cylinder B², onto the bottom ring b³, and securing the parts by screwing said top ring b' to the partitions b³. The ends of the yoke Y are now passed into two diametrically-opposite hook or eye bolts b⁶ and 20 the basket hoisted and moved along the rail R' over the filling-drum D, into the outer annular space of which it is lowered, and the funnels F introduced into the recesses d⁴, formed in the inner wall of the filling-drum D.

25 In lowering the basket into drum D care should be had that the apices of the partitions b³ and b⁴ will lie centrally of the recesses d⁴, so that a recess will serve to fill the spaces in the two compartments on opposite sides of a 30 partition, thereby dispensing with one-half of the recesses otherwise necessary to fill the spaces in all the compartments. The width of the annular space in which the basket is received is but a trifle greater than that of the shelves or mold portion so as leave as 35 little superfluous space as possible. It will also be seen by an inspection of Fig. I that the filling-drum has near its upper edge an annular flange c⁵, upon which seats the over-40 hanging flange b⁸ on the top ring of the basket B, forming a practically tight joint at that point, and as the inner edge of the top ring b' of the basket, which is provided with an upturned annular flange b⁹ and the 45 shelves B', fits almost tight against the inner wall of the filling-drum there will be just space enough left for the circulation of the masse-cuite and the escape of air. After the spaces between the shelves are filled, except 50 the space between the upper shelf and the top ring b', the supply of masse-cuite is cut off, the funnels F are withdrawn, and the forcing-bars E, which are of such dimensions as to snugly fit into the recesses d⁴ of the filling-drum, are introduced into said recesses, thereby forcing what masse-cuite may be outside of the forms into the upper one, and at the same time expelling any air or air bubbles in the said masse-cuite, which is now allowed 55 to rest a sufficient length of time to solidify before mounting the basket on the centrifugal drum CD, which I will now describe, referring to Figs. III, V, VII, and VIII.

The centrifugal drum CD is a cylindrical body provided with an annular flange f, in 60 which is secured a rail f' for the support of

the bottom rib b⁷ of the basket B, as shown in Figs. V and VII. This rail may, however, be dispensed with, if desired, as it is not absolutely necessary, though I prefer to use it 70 as a bearing for the basket to prevent wear of the foot-flange of the drum.

In practice the bearing-rail f' is constructed of rubber to better resist any tendency of the basket to revolve on the drum and to form a 75 tight joint between the two. From the rail upwardly the outer face of the drum is inclined, as shown at f², Fig. V, said inclined portion serving as a bearing for the correspondingly-inclined inner face of the bottom 80 ring of the basket B.

The drum CD is provided with an axial socket-bearing f⁴ for the driving-shaft S, that may be driven from any suitable prime motor belted to pulley P', and above said socket 85 the drum is provided with hollow radial arms f³, that are open at the periphery and inter-communicate at their points of intersection, at which point there is provided a stuffing-box f⁵, in which is loosely seated a pipe p, 90 screw-threaded at its outer end and provided with a flange at its inner end, which pipe is adapted to be connected to a stop-cock C, Figs. VII and VIII, by means of a screw-coupling c, Fig. VII, said stop-cock C being secured to 95 a pipe P, that is connected to the reservoir R, that contains the fine liquor, as shown in Fig. XI. To the inner periphery of the drum, at its upper end, are pivoted coupling-bolts f⁷, adapted to enter holes in a locking-ring LR, 100 in the under side of which is formed an annular groove that fits over the upper edge of the drum and over the upturned flange b⁹ on the basket B (see Fig. VII) to lock the basket firmly to the drum through the medium of the 105 bolts f⁷ and suitable nuts, as shown in Fig. VII.

In practice the centrifugal drum CD is enclosed in a suitable housing or casing H', provided with a lid or cover h, Figs. V and VII, 110 and below the drum is arranged a drip-board h' to catch the green sirup and the fine liquor eliminated from the slabs of sugar in the basket B by centrifugal action. In practice I also interpose a measuring-vessel in the pipe-connection for conducting the fine liquor to 115 the basket, which measuring-vessel I have deemed unnecessary to show in the drawings, as the use and construction thereof are well known. 120

The operation of clearing or purifying the slabs of sugar may be briefly described as follows: After the basket has been secured to the centrifugal drum CD, as described, the centrifugal is spun to remove the green sirup 125 from the slabs, which is usually effected in about fifteen minutes, after which the stop-cock C on pipe P' is coupled to pipe p, which may be done without stopping the rotation of the centrifugal, the pipe p, as described, 130 being so connected with the stuffing-box as not to rotate therewith, it being sufficiently

loose in the stuffing-box f^5 for this purpose. The fine liquor will thus be admitted to the radial arms f^3 under considerable pressure, the reservoir for the liquor being in practice located about ten meters above the centrifugal. As shown in Fig. VII, the basket fits almost tight upon the drum CD, there being but a narrow annular space f^{21} between said drum and the inner end of the shelves, so that but a comparatively small quantity of fine liquor can circulate therein, but, owing to its being supplied under considerable pressure, is equally distributed throughout the annular space and forced through the slabs of sugar on the shelves B', the passage through the sugar of the fine liquor being assisted and accelerated by the centrifugal action. As the fine liquor is supplied from within only, its passage through the sugar is very rapid and carries any impurities or green syrup with it, the passage of the liquor through the sugar taking place in a few minutes, usually about two or three minutes. The quantity of fine liquor supplied to the centrifugal is measured in the measuring-vessel referred to, and one-fourth of a liter per kilogram of sugar is usually required. As soon as the measuring-vessel is empty the stop-cock C is closed and disconnected from the centrifugal, which is kept in rotation for about twenty minutes more to remove all of the fine liquor, when its rotation is stopped, and the basket lifted off and transported to the table T. To this end the nuts of the pivoted bolts f^7 are unscrewed and the locking-ring LR removed. The ends of the yoke Y are then inserted into two of the hook or eye bolts b^6 . The basket is hoisted by means of the rack-bar RB and gearing and moved along the rail R to the table T, onto which it is lowered. The basket may now be dismantled by simply unscrewing the hook or eye bolts b^6 from the partitions b^3 and the yoke Y again hoisted, thereby lifting the foraminous cylinder, together with the top ring b^1 and partitions b^4 , off the base or bottom ring b^2 of the basket, leaving the shelves with the slabs of purified sugar thereon exposed for ready removal to the drier. When the purification or clearing is to be effected by steam, the space between the basket B and the centrifugal drum CD is slightly increased by making the body of the drum more or less conical, as shown in Fig. IX, the radial arms f^3 being shortened and bent downward to discharge the steam into the drum CD, from which it then rises over the top thereof into the space f^{21} between the drum and basket and passes thence through the slabs of sugar. In this construction instead of a locking-ring LR a locking-disk LD is used to completely close the top of the drum, which is also provided in its bottom with a valved passage or pipe p' for drawing off the water of condensation. The conical form of the drum CD insures a uniform

steam-pressure upon its exterior, and consequently upon the slabs or tablets of sugar.

From an inspection of Fig. IX it will be seen that the body of the centrifugal drum CD is detachably connected with the base f^{13} , and this construction I prefer, for the reason that either a cylindrical or a conical drum-body may be applied to the base for purifying, either by means of fine liquor or by means of steam, or by both, if necessary. In Fig. IX I have also shown a foraminous cylinder B² as connected with the centrifugal drum CD and the top plate or ring b' of the basket B as provided with apertures b , one for each vertical compartment, for the purpose of filling the same, suitable funnels being inserted into the said apertures, which, when the basket is filled, are closed by caps c' , secured in position by means of bolts c^2 and nuts c^3 , having eyes formed thereon. The radial hollow arms f^3 are also shown in said Fig. IX as detachably secured to the tubular bearing or socket f^4 for the driving-shaft S, so that radial arms such as shown in Fig. V may be substituted therefor whenever the purification is effected by means of fine liquor instead of steam.

Instead of arranging the shelves B' horizontally, they may be arranged vertically, the top ring b' and the bottom ring b^2 of the basket B being suitably grooved for the reception of the vertical partitions B³, as shown at b^{15} , Fig. IX, and, as shown, the grooves do not extend to the inner periphery of the top and bottom rings, thus forming stop-shoulders to prevent the partitions being pushed in too far, each partition having a head and foot extension $b^{16} b^{17}$ of the same length as and adapted to fit into said grooves. Furthermore, each of the vertical partitions B³ is provided about midway of its length with a cross-brace b^{18} , that serves to brace the partitions transversely, and with an abutment or spacing block or brace b^{19} , that holds the partitions against bending or warping.

Having thus described my invention, what I claim is—

1. In the purification of sugar, the herein-described basket for the centrifugal machine, comprising a top and bottom ring, a foraminous cylinder connected with said rings, a plurality of radial partitions alternately secured to the bottom and top rings, respectively, and extending from the cylinder toward the axis of the basket, and a locking device for detachably locking to the top ring those vertical partitions which are secured to the bottom ring, substantially as and for the purposes specified.

2. In the purification of sugar, the herein-described basket for the centrifugal machine, comprising a top and bottom ring, a foraminous cylinder connected with said rings, a plurality of vertical partitions wedge-shaped in cross-section extending from the cylinder toward the axis of the basket, the inclination of said partitions being such as to form rect-

angular spaces between them, the outer side of which is segmental, said rings being alternately secured to the top and bottom rings, and a locking device to lock to the top ring 5 those partitions which are secured to the bottom ring, substantially as and for the purpose specified.

3. In the purification of sugar, the herein-described basket for centrifugal machines, comprising a top and bottom ring, a foraminous cylinder connected with said rings, a plurality of vertical partitions secured alternately to said top and bottom rings and extending from the cylinder toward the axis of 15 the basket, a locking device for locking to the top ring those partitions which are secured to the bottom ring, and removable sheet-metal partitions for dividing the space between the vertical partitions, substantially 20 as and for the purpose specified.

4. In the purification of sugar, the herein-described basket for the centrifugal machine, comprising a top and bottom ring, a foraminous cylinder connected with said rings, a plurality of vertical partitions wedge-shaped in cross-section and extending radially from the cylinder toward the axis of the basket, said partitions being alternately secured to said top and bottom rings, the inclination of the 25 partitions being such as to form substantially rectangular spaces between them, the outer side of which is segmental, and removable sheet-metal partitions for dividing the said 30 spaces, substantially as and for the purpose specified.

5. In the purification of sugar, the herein-described basket for the centrifugal machine, comprising a top and bottom ring, a foraminous cylinder seated loosely on the bottom 40 ring and secured rigidly to the top ring and vertical partitions secured alternately to said top and bottom rings, and a locking device for detachably securing to the top ring those partitions which are secured to the bottom 45 ring, substantially as and for the purposes specified.

6. In the purification of sugar, the herein-described basket for the centrifugal machine, comprising a top and bottom ring, a foraminous cylinder seated loosely on the bottom 50 ring and connected rigidly to the top ring, vertical partitions wedge-shaped in cross-section extending radially from the cylinder toward the axis of the basket, the inclination 55 of the sides of the partitions being such as to form substantially rectangular spaces between them, having their outer side segmental, and a locking device for detachably locking to the top ring those partitions which 60 are secured to the bottom ring, substantially as and for the purpose specified.

7. In the purification of sugar, the herein-described basket for the centrifugal machine, comprising a top and bottom ring, a foraminous cylinder seated loosely on the bottom 65 ring and secured rigidly to the top ring, ver-

tical partitions b^3 , rigidly secured to the bottom ring, like partitions b^4 , detachably connected to the top ring, and hook or eye bolts b^6 for connecting the partitions b^3 and b^4 to said top ring, substantially as and for the purpose specified.

8. In the purification of sugar, the combination, with a basket consisting, essentially, of a cylinder whose outer periphery is composed of a foraminous material, said cylinder being divided into chambers open at their inner ends for containing the forms, and provided with an annular foot-flange, the inner face of which is inclined, in combination with a filling-drum comprising two concentric cylinders forming an annular chamber for the reception of the cylindrical basket, said chamber being provided in its bottom with an annular recess for the reception of the foot-flange of the basket and with a duct or passage leading from said recess to the exterior of the drum, the inner cylinder of which is provided with rectangular recesses d^4 , substantially as and for the purpose specified.

9. In the purification of sugar, the combination, with the described cylindrical basket B, having its chambers containing the forms open at their inner end, of a filling-drum composed of two concentric cylinders, the inner 95 cylinder having vertical recesses d^4 formed in its walls, said recesses straddling the partitions of the basket-chambers, and the forcing-bars E, constructed to fit into said recesses, substantially as and for the purpose specified.

10. In the purification of sugar, the combination, with the cylindrical basket B, containing the forms and having an annular base or foot flange b^7 in its bottom ring b^2 , the 105 inner face of which flange is inclined, of the centrifugal drum provided with a base-flange having the inclined seat f^2 and the annular gasket f' , substantially as and for the purpose specified.

11. In the purification of sugar, the combination, with the cylindrical basket B, containing the forms, the top ring b' of said basket being provided with a vertical flange b^9 at its inner periphery, a revoluble drum 115 provided with a suitable seat for the basket and with a corresponding vertical flange, and locking-bolts f^7 , pivoted at the upper edge of the drum, of a locking plate or ring provided with an annular groove adapted to fit over 120 the flanges of the drum and basket, and with holes for the passage of the pivoted bolts, and nuts for locking the ring to the bolts, substantially as and for the purpose specified.

12. The basket B, comprising top and bottom rings, a foraminous cylinder connected therewith, radial vertical partitions b^3 b^4 , secured to said top and bottom rings and adapted to divide the same into substantially rectangular spaces, radial grooves formed in the 130 proximate faces of said rings between the partitions b^3 b^4 , and sheet-metal partitions B^3 ,

adapted to fit into said grooves to divide the space between the partitions b^3 b^4 , substantially as and for the purpose specified.

13. The drum CD, comprising a base f^{13} , having an axial tubular bearing, radial tubular arms f^3 , detachably connected with said bearing, a substantially cylindrical body detachably connected with the base, and bolts hinged to said body at or near its upper edge,

substantially as and for the purpose specified.

In testimony whereof I affix my signature in presence of two witnesses.

GUSTAVE ADANT.
